UNITED STATES PATENT OFFICE.

JOSEPH WHITE, OF PISCATAWAY TOWNSHIP, NEW JERSEY, ASSIGNOR TO HALL PRINTING PRESS COMPANY, OF DUNELLEN, NEW JERSEY, A CORPORATION OF NEW JERSEY.

PRINTING-PRESS.

1,158,761.

Specification of Letters Patent.

Patented Nov. 2, 1915.

Application filed May 5, 1913. Serial No. 765,414.

To all whom it may concern:

Be it known that I, JOSEPH WHITE, a citizen of the United States, residing in Piscataway township, State of New Jersey, 5 (post-office address Bound Brook, New Jersey), have invented certain new and useful Improvements in Printing-Presses; and I do declare the following to be a full, true, and exact description of the said invention, 10 such as will enable others skilled in the art to which it appertains to make use of the same.

This present invention relates to any form 15 of sheet handling device in which it is necessary to feed sheets to sheet taking mechanism with a definite relation to such mechanism, and one of the objects of my invention is to provide means by which to throw out the impression in a printing press on 20 the failure of a flow of sheets thereto, or on one or more sheets being presented to the press in inaccurate relation thereto for printing in register, and for throwing in the impression when sheets are properly 25 presented.

Another object of the invention is to provide means, in sheet handling devices into 30 which sheets are forwarded one by one, by automatic or semi-automatic means, to divert from its normal path, a sheet not properly presented to such sheet handling machinery. This is desirable so that such misplaced sheets shall not go into the same pile 35 as sheets which have been properly presented, and particularly in printing presses provided with a mechanism for tripping the impression, so that sheets, when not properly presented, will not pass in an unprinted condition into the pile of regularly printed sheets.

I have also provided a novel form of 40 mechanism by which the tripping mechanism or the sheet diverter, or both, will be under the automatic control of sheets being presented to the sheet handling mechanism.

With these and other objects in view my 45 invention consists of certain novel features of construction, combination and arrangement of parts as will be more fully described 50 and pointed out in the appended claims.

In the drawings, Figure 1 represents a side elevation of a portion of one form of printing press which I have chosen for pur-

poses of illustration, showing my novel features in relation thereto as they would be 55 when a sheet has been properly presented to the sheet taking device. Fig. 2 is the same as Fig. 1, except that the parts are shown as they would be if a sheet has not been properly presented to the sheet taking device. Fig. 3 represents an enlarged portion of Fig. 1 showing the parts in the relation they would be if a sheet has not been properly presented. Fig. 4 shows the relation of the sheet when it has been properly 60 presented and Fig. 5 shows an end elevation of Fig. 4. Figs. 6 and 7 represent two views of a preferred form of tape driving and supporting mechanism.

The corresponding parts are referred to 70 both in the drawings and specification by similar reference characters.

Referring now to the drawings, 10 represents an impression cylinder and 11 a form cylinder, the latter being provided with 75 suitable inking and water rollers, customary in the planographic printing press, which I have chosen for purposes of illustration. These two cylinders are geared together in the usual manner to form a printing couple 80 and arranged to print the sheets fed to the lower side of the cylinder 10, and to deliver such sheets in the usual manner through the rollers and tapes shown at the top of the cylinder 10. 85

The impression cylinder 10 is provided with the usual set of gripper fingers 12 normally held closed on the impression surface of the cylinder 10 by the spring 13 acting on the lever 14. The shaft supporting the 90 fingers 12 is provided with the usual cam lever and cam roller 15 controlled by the cam 16 loosely mounted on the center of the cylinder 10 for a purpose to be hereinafter described. During the normal operation of 95 the press, the cam 16 is held in the position shown in Fig. 1 so that the fingers 12, under the pressure of the spring 13, normally close at the point indicated in Fig. 1 and open to release the sheet at the top of the cylinder 100 10 of Fig. 1.

The cylinder 10 is mounted in eccentric boxes in the usual manner, each of these boxes being connected through lever 17 and link 18 with a lever 19 attached to a shaft 105 20. As will be seen by an inspection of Figs.

1 and 2, the shaft 20 rotates the eccentric bushings and thus trips the impression between the cylinders 10 and 11. This partial rotation of the shaft 20, back and forth, to trip and untrip the impression is brought about by the operation of a fork 21 connected at one end to an eccentric 22 attached to a shaft 23. This shaft is geared to the cylinder 11, in the form illustrated, in the 10 ratio of three to one. Thus the fork 21 makes three complete reciprocations for each rotation of the cylinders 10 and 11. Mounted on the shaft 20 and attached thereto is a double ended lever 24 carrying pins 25 and 26. The fork 21 is provided with notches on either side thereof, moving in the planes of the pins 25 and 26 and arranged to connect with either one of them according to whether the fork 21 is raised or lowered. In 15 the position shown in Fig. 1, the fork has been held in its upward position so that the upper notch has engaged with the pin 26 to turn the lever 24 to the position shown in Fig. 1. So long as the fork 21 is held in its 20 upward position, the further repeated reciprocations thereof will not affect the position of the lever 24. If, however, the fork 21 is moved downwardly, it will, on its next forward motion, engage with the pin 25 25 through the lower notch of the fork and the lever 24 will be turned to the position shown in Fig. 2. The raising of the fork 21 will again restore the lever 24 to the position shown in Fig. 1. Thus the moving of the 30 fork 21 up and down serves to trip or untrip the impression between the cylinders 10 and 11.

Shafts 30 and 31 at the left of Figs. 1 and 2 extend across the frames of the machine 35 and are provided with sprockets carrying, preferably, a pair of chains 32, one at either side of the machine. Through the gears 33, 34, and 35, the shaft 31 is rotated, causing the upper portion of the chain extending between the shafts 30 and 31 to travel toward the cylinder 10. On centers 36 and 37 are supported a series of tape pulleys 38 and 39 driven in any suitable manner, and preferably, as shown in Figs. 6 and 7 as described 40 hereinafter, through the gearing shown at the left of Fig. 1, so that the upper portion of the tapes passing around these sets of pulleys will also move toward the cylinder 10. These tapes serve as a support to carry 45 the sheets placed thereon and move such sheets toward the sheet taking point of the impression cylinder 10. In addition, I provide a series of flat bars 41 to support the sheet, these bars extending up to and beyond the closing point of grippers 12. On the 50 chain 32 is carried a gaging mechanism shown in enlarged views in Figs. 3, 4, and 5. This gaging mechanism includes a sheet front gage 40 attached to the chain in such 55 a manner that it moves in the path of the sheet carried by the tapes on the pulleys 38 and 39. The gage 40 is provided with an overguide 42 to direct the sheet against the gage 40, and, as will be seen by an inspection of Fig. 1, moves in the plane of a sheet forwarded by the tapes and is moved at a speed slower than that given to the sheets by the tapes. Thus the sheet, because of this difference in speed, is pushed by the tapes against the front gage 40 while it is being 60 conveyed to the taking point of the impression cylinder 10. Also carried by the chain 32 and pivotally mounted thereon adjacent the gage 40 is an arm 43 of a lever carrying at its opposite end a projection 44. The weight of the projection 44 is sufficient to normally hold the arm 43 in the position shown in Fig. 3. But the two arms 43 and 44 are balanced so that when a sheet S is moved against the gage 40, the arm 43, is 65 moved to the position shown in Fig. 4, thus swinging the projection 44 to the position shown in Fig. 4. Hence, if, at a predetermined point in the travel of the gage 40, a sheet is not presented thereto so as to be in 70 correct relation therewith, the projection 44 stands in the position shown in Fig. 3, whereas if the sheet has been properly presented, it stands in the position shown in Fig. 4. To insure this action, I preferably provide 75 a plate 45 suitably supported on the side frame of the machine on the rod 46 and extending in the path of the projection 44. The edges of the plate 45 are sharpened so that the projection 44 will move either above 80 the plate 45 or below it, and when the projection 44 is moving below the plate 45, it is able to resist the pressure of the mechanism now about to be described.

Extending across the side frames of the 85 press are two shafts 47 and 48. To the shaft 48 is attached a lever 49 connected by a rod 50 to one end of the lever 51 carrying a cam roller 52 moved by a cam 53, this cam being 90 adjustably attached to the cylinder 11. As will be seen by an inspection of Fig. 1, the cam 53 gives to the shaft 48 a continuous reciprocating motion. Attached to the shaft 48 is a lever 54 carrying at one end a pivoted member 55, weighted by the arm 56 so as 95 to hang normally in the position shown in Fig. 4. The pivoted member 55 is provided with an upper arm 57 arranged to be engaged by the projection 44 when the latter is traveling beneath the plate 45 to swing the pivoted member 55 to the position shown in 100 Fig. 3. Attached to the shaft 47 is a lever 58 carrying at its end a vertically movable pin 59 having a head 60 carrying a notch 61. This headed pin is held normally in the 105 position shown in Figs. 3 and 4 by a flat spring 62. The pivoted member 55 is provided with a lower arm 63 extending in the 110 plane of the head 60, as shown in Figs. 3 and 4. The projection 44, moving below the 115

plate 45, serves to swing the pivoted member 55 so that the arm 63 is moved from the position shown in Fig. 4 into the position shown in Fig. 3, the spring 62 permitting the head 60 to be pushed downward to allow the arm 63 to snap into the notch 61 and into the position shown in Fig. 3. When the parts are in this position, the shaft 48 is rotated by the cam 53 and the arm 54, swinging downward, carries with it through the arm 63 and the headed pin 60, the arm 58, thus partially rotating the shaft 47. Attached to the shaft 47 is a lever 64, connected through a rod 65 with a bell crank 66, connected in turn yieldingly through a rod 67 with the fork 21. The partial rotation of the shaft 47 from the position shown in Fig. 1 to the position shown in Fig. 2 thus permits the fork 21 to drop so that at its next forward reciprocation, it will engage with the pin 25 to rotate the eccentric bearings of the cylinder 10 to trip the impression. An inspection of Fig. 3 will show, however, that the projection 44 is not in the position shown in that figure unless no sheet has been properly presented to the gage 40, so that the failure to so present a sheet results in the tripping of the impression.

As the cam roller 52 passes to the lowest part of cam 53, spring 68 turns the shaft 48 so that the lever 54 swings to its upper position as shown in Fig. 4. This permits the lever 58 to rise also, a spring 69 causing the shaft 47 to turn. This causes the fork 21 to be raised to its upward position as shown in Fig. 1. If no sheet is again presented to the gage 40 as it again returns to the position shown in Figs. 3 and 4, the projection 44 again moves the arm 63 into the notch 61 so that the downward motion of the arm 54 carries the lever 58 with it, and the fork 21 is permitted to drop before engaging with the pin 26. The cylinder thus remains in a tripped position until a sheet has been presented properly to the gage 40. In such case, the arm 63 does not engage with the notch 61, so that, when the lever 58 is moved downward, the shaft 47 is not disturbed and the fork 21 thus engages with the pin 26 to move the lever 24 into the position shown in Fig. 1 from the position shown in Fig. 2. A continual supply of sheets prevents the engagement of the arm 63 with the notch 61 so that the impression remains on.

56 The upward position of the lever 58 is determined by a suitable stop such as I have shown in the form of a collar 70 attached to the spring rod of the spring 69 and set so as to strike a puppet 71 in the side frame of the machine, thus limiting the upward motion of the lever 58. This cam 53 is designed so that the lever 54 first swings upwardly far enough to permit the arm 63 to be some distance above the topmost position 65 of the notch 61, so that the weight 66 may

act to swing the arm 63 out of the notch 61 into the position shown in Fig. 4, the stop collar 70 being set so as to limit the upper position of lever 58 for that purpose. On the further rotation of the cam 53, a high portion 72 is reached by the cam roller 52, which causes the arm 54 to be swung downward into the position shown in Fig. 4 ready to be acted upon by the projection 44 when the latter passes below the plate 45.

It should be understood that when I speak of a sheet being properly positioned against the gage 40, I mean that it shall be placed exactly thereagainst so that it will be in correct register with the impression cylinder 10 when delivered thereto. It will also be understood that the mechanism shown in Figs. 3 and 4 will be preferably duplicated on either side of the press so that, if a sheet be properly presented to one gage 40, for instance, at the right hand side of the press, and not presented properly to the gage 40 at the left hand side of the press, the shaft 47 will be rotated to trip the impression. By this means, a sheet which is not in proper relation throughout its length crosswise of the press will cause the cylinders to separate. If such a sheet were taken by the grippers 12 at the feeding point, the machine might be clogged by reason of the grippers failing to hold the sheet properly. Moreover, if such sheet were carried around to the delivery tapes, it would be a blank sheet since the impression would be tripped and this blank sheet would be deposited in the regular delivery pile. It is therefore desirable to prevent or withhold the action of the grippers 12 so that the sheet will not be carried around the impression cylinder 10, and it is also desirable that such wrongly positioned sheets shall be thrown out of the press before being carried to the delivery pile. Either of these features alone is desirable but I prefer to combine them and I have provided mechanism for that purpose. As has been pointed out before, the gripper cam 16 is loosely mounted on the center of the cylinder 10. Through a lever 75 and a connecting rod 76, the cam 16 is connected to a lever 77 attached to the shaft 20. When the shaft 20 is rotated so as to separate the printing couple, the cam 16 is moved from the position shown in Fig. 1 to the position shown in Fig. 2. The grippers 12 are thereby prevented from closing at the usual sheet taking point and are permitted to close only after such point has been passed, as will be shown by an inspection of Fig. 2. Thus an irregularly positioned sheet will not be taken by the grippers 12 since the shaft 20 is caused to rotate into the position shown in Fig. 2 when the sheet is not presented properly to the front gages 40. As a means for diverting a wrongly deposited sheet from the path of the properly positioned sheets, 130

I provide on the shaft 20 one or more arms or switches 78. These arms are so proportioned and arranged as to be swung from the position shown in Fig. 1 to the position 5 shown in Fig. 2 whenever a sheet is not properly presented to the gages 40. The arms 78 thus become overguides which engage a sheet and throw it downwardly instead of permitting it to pass upwardly and 10 around the cylinder 10. When a sheet is properly presented to the gages 40, the rotation of the shaft 20 throws the arms 78 into the position shown in Fig. 1, the sheet then passing around the cylinder 10.

15 In Figs. 6 and 7 I have shown a preferred form of supporting and driving the sheet forwarding tapes shown at the left of Figs. 1 and 2, although it will be understood that any usual form of such mechanism may be 20 used in connection with my invention. I have found the special arrangement shown in Figs. 6 and 7, however, convenient and simple in operation, and one which enables me to locate the tapes and the supports 41 25 in any desired position without requiring the displacement of any other portions of the mechanism. Indeed, in some forms of sheet forwarding devices where it becomes necessary to move certain parts, such as 30 guides and gages, cross-wise of the machine, it becomes necessary to have these tapes and sheet supports removable, so that such side shifting may take place. The shafts 80, 81 are fixed in the side frame of the machine.

35 Arranged to be adjustably and removably held are supports 82, 83, these supports being provided with set screws to fasten them to the shafts but having a portion of their bearing on the shafts 80, 81 cut away so that 40 they may be readily removed. These supports 82, 83 are attached to the sheet support 41, which therefore forms a connection between them, the support 41 being rigid enough to act as a tie. On the support 82 is 45 rotatably mounted the pulley 38 and attached to the support 41 is a pulley support 84 on which is rotatably mounted the pulley 39. This support 84 is longitudinally adjustable on the sheet support 41 and is held in 50 adjusted position by the bolt 85. A tape passes around the pulleys 38 and 39 in the usual manner and may be tightened by shifting the support 84 on the sheet support 41. Preferably slots are cut in the sheet support 41 so that the belt may pass along the top 55 surface thereof instead of at one side although the latter construction is sometimes desirable. By providing the arrangement which I have shown, however, the belt becomes simply a forwarding device being held in its proper position by the rigid sheet support 41.

60 As will be seen from the arrangement just described, the loosening of the set screws 65 in the supports 82, 83 permit these supports

and the bar 41, together with the tapes and pulleys supported thereon, to be moved upwardly and away from the bars 80, 81 without disturbing the arrangement of the tapes and pulleys. On re-inserting shafts 80, 81 70 into the supports 82, 83, and tightening the screws, the tapes and supports will be again in their proper positions. It is necessary to drive the tape at a definite speed, and as a means for driving these pulleys, which will 75 not be disturbed by the removal of the pulleys therefrom in shifting them from place to place, and which will readily permit such removal, I provide a constantly rotating shaft 86 in the form of a pipe roller suitably 80 rotatably supported in the side frames of the machine, and located so that the tape in passing around the pulley 39 contacts with the roller 86, and is nipped between that roller and the pulley 39. This serves as a 85 frictional drive for the tape, but one from which the pulley 39 can be readily removed and returned without in any way disturbing it, as will be obvious. The proper speed of rotation is given to the shaft 86 through the 90 gearing 87, 88, 89, 90, 91, the latter gear being attached to the shaft 30 carrying the sprockets for the chains 32.

95 It will be understood that many features of my invention would be useful in any kind of a sheet handling mechanism, such as folders or the like, and that the specific mechanism for carrying out such invention may vary within wide limits. It will also be understood that many features of my 100 invention may be used independently of other features. For instance, for many purposes it will be sufficient to merely control the action of the sheet taking device so that a sheet not properly positioned will not be 105 taken by such device. It will also be understood that in many machines it will be sufficient to merely trip the impression or even to use the sheet diverting arms 78 alone to 110 throw an irregularly positioned sheet out of the machine. It should also be understood that while I have shown these features of my invention as controlled automatically by a sheet being presented to the impression cylinder, it is possible to use such features 115 in connection with a foot trip operated by the feeder of the machine. It will also be understood that my arrangement for supporting and driving the sheet forwarding tapes shown in Figs. 6 and 7 may be used in 120 any kind of a machine in which it is desirable that such tapes shall be readily removable from the machine without disturbing the connection between such tapes and their driving mechanism.

125 Having now described my invention, what I claim as new and desire to secure by Letters Patent is as follows:

1. A rotary sheet carrier, a set of sheet grippers thereon, means, including a cam, to 130

- cause said grippers to close normally at each cycle of said carrier at a predetermined point in the travel thereof, and means, controlled by a sheet being presented to said grippers, to cause the closing of said grippers to be delayed in each cycle of said carrier, when the sheet is improperly presented to said grippers, until said grippers have passed said predetermined point.
10. 2. Sheet taking means, means to move said sheet taking means, means to operate said sheet taking means at a predetermined point in their path of travel, means to move a sheet toward said sheet taking means, a gage, means to move said gage with the sheet and in the path thereof in timed relation with said sheet taking means and mechanically operated means, withheld from action by a sheet against said gage, to prevent the operation of said sheet taking means at said predetermined point.
15. 3. Means to forward a sheet along a predetermined path, a gage moving with the sheet in said path, and means, withheld from action by a sheet against said gage while the sheet is under the control of said forwarding means, to divert a sheet from said path.
20. 4. A printing couple, means to forward a sheet along a predetermined path toward said couple, means to divert a sheet from said path before it reaches said couple, means operating normally to move said diverting means into operative position, and means, extending into said path and arranged to be moved by the advance of a sheet under control of said sheet-forwarding means, to suspend the action of said normally operating means.
25. 5. Means to forward a sheet along a predetermined path, means to divert a sheet from said path, and means, moving with the sheet and extending into the path thereof while it is under control of said forwarding means, to operate said sheet-diverting means.
30. 6. Means to support and move a sheet over any one of a plurality of paths, a gage moving with the sheet and means, operable while the sheet is in the control of said forwarding means, to select automatically the path to be followed by the sheet, in accordance with the position of the sheet in relation to said gage.
35. 7. A sheet carrier having sheet taking means thereon, means to move a sheet toward the taking point of said sheet taking means, a gage moving in the path of the sheet and arranged to position the sheet in correct relation with said sheet taking means and means arranged to be operated before the sheet reaches said taking point to divert the sheet therefrom when the sheet has not been positioned against said gage.
40. 8. Sheet taking means, means to move said sheet taking means, means to operate said sheet taking means at a predetermined point in their path of travel, means to move a sheet toward said sheet taking means, a gage in the path of said sheet and moving therewith, and means, adapted to be withheld from action by a sheet against said gage, to prevent the operation of said sheet taking means at said predetermined point and to alter the path of a sheet not positioned against said gage.
45. 9. A sheet carrier, sheet grippers thereon, means to move a sheet toward the feeding point of said carrier, means to close said grippers at said feeding point, a gage in the path of the sheet and moving therewith, and means, adapted to be withheld from action by a sheet against said gage, to prevent the closing of said grippers at said feeding point and to divert therefrom a sheet not positioned against said gage.
50. 10. A printing couple, means to forward a sheet along a predetermined path to said couple, a gage moving with and in the path of the sheet, and means adapted to be withheld from action by the presence of a sheet against said gage, to divert from said predetermined path a sheet under the control of said forwarding means not positioned against said gage and to separate said couple.
55. 11. A printing couple, means to separate said couple, means to forward a sheet toward said couple, means to control the path of the sheet, a gage moving with and in the path of the sheet, and means, adapted to be controlled by the presence against said gage of a sheet under the control of said forwarding means, to control the operation of said couple separating means and said path controlling means.
60. 12. A printing couple, means to separate said couple, means to forward a sheet toward said couple, a gage, means to move said gage with the sheet and in timed relation to said couple, means to control the path of the sheet and means adapted to be controlled by the position in relation to said gage of the sheet while under control of said forwarding means to operate said couple separating means and said path controlling means.
65. 13. A printing couple having sheet taking means thereon, means to forward a sheet toward the taking point of said sheet taking means, means to separate said couple, means to control the path of the sheet, and means, controlled by the position in relation to said sheet taking means of a sheet while under the control of said forwarding means, to operate said couple separating means and said path controlling means.
70. 14. A printing couple having sheet taking means thereon, means to operate said sheet taking means at a predetermined point in their path of travel, means to separate said couple, means to forward a sheet continuously toward and into said sheet taking means.

means, and mechanically operated means, extending into the path of the sheet, to operate said couple separating means and to prevent the operation of said sheet taking means at said predetermined point.

- 5 15. A printing couple having sheet taking means thereon, means to operate said sheet taking means at a predetermined point in their path of travel, means to separate said couple, means to forward a sheet continuously toward and into said sheet taking means, a gage, and mechanically operated means, controlled by the position of the sheet in relation to said gage while the sheet is 10 under the control of said forwarding means, to operate said couple separating means and to prevent the operation of said sheet taking means at said predetermined point.

- 20 16. A printing couple having sheet taking means thereon, means to close said sheet taking means at a predetermined point in their path of travel, means to separate said couple, means to forward a sheet toward the point of operation of said sheet taking means, a 25 gage, means to move said gage with the sheet and in the path thereof in timed relation to said sheet taking means, and mechanically operated means, controlled by the position of a sheet in relation to said gage, to 30 operate said couple separating means and to prevent the closing of said sheet taking means at said predetermined point.

- 35 17. A printing couple having sheet taking means thereon, means to operate said sheet taking means at a predetermined point in their travel, means to separate said couple, means to forward a sheet toward the taking point of said sheet taking means, means to control the path of the sheet, and means, extending into the path of the sheet while under the control of said forwarding means to operate said couple separating means and said path controlling means and to prevent the operation of said sheet taking means at 40 45 said predetermined point.

- 50 18. A printing couple having sheet taking means thereon, means to forward a sheet to said couple, means to operate said sheet taking means at a predetermined point in their travel, means to separate said couple, a gage, means to control the path of a sheet between said gage and said sheet taking means and means, controlled by the position in relation to said gage of a sheet under the control of 55 said forwarding means, to operate said couple separating means and said path controlling means and to prevent the operation of said sheet taking means at said predetermined point.

- 60 65 19. A printing couple, having sheet taking means thereon, means to operate said sheet taking means at a predetermined point in their travel, means to separate said couple, means to forward a sheet toward the taking point of said sheet taking means, means to

control the path of the sheet, a gage, means to move said gage with and in the path of the sheet in timed relation to said sheet taking means, and means, controlled by the position in relation to said gage of a sheet 70 under the control of said sheet moving means, to operate said couple separating means and said path controlling means and to prevent the operation of said sheet taking means at said predetermined point.

75 20. A printing couple, means to separate said couple, a support for a sheet being fed to said couple, a continuously moving gage in the path of the sheet on said support and traveling with the sheet independently of 80 said support, and means, controlled by the sheet being fed, to operate said couple separating means according to whether or not the sheet is positioned against said gage at a predetermined point in said gage's travel 85 before it reaches said couple.

90 21. A printing couple, means to separate said couple, a support for a sheet being fed to said couple, a continuously moving pair of sheet front gages in the path of the sheet on said support and traveling with the sheet independently of said support, and means, controlled by the sheet being fed, to operate said couple separating means according to whether or not the sheet is positioned 95 against both of said gages at a predetermined point in their travel before they reach said couple.

100 22. A printing couple, means to separate said couple, a support for a sheet being fed to said couple, means to forward a sheet along said support, an endless belt supported so that a portion thereof is parallel with said support, means to move said belt continuously, and means, mounted on said belt and arranged to 105 extend into the path of a sheet on said support to be operated by a sheet under the control of said forwarding means, to control the operation of said couple separating means.

110 23. A printing couple, means to separate said couple, a support for a sheet being fed to said couple, means to forward a sheet along said support, an endless belt arranged so that a portion thereof is parallel with 115 said support, means to move said belt continuously in timed relation to said couple, a gage mounted on said belt and arranged to move in the path of a sheet on said support, and means, mounted on said belt adjacent said gage, to control the operation of said couple separating means according to whether a sheet under control of said forwarding means is present or absent from said gage at a predetermined point in its 120 travel.

125 24. A printing couple, means to separate said couple, a support for a sheet being fed to said couple, means to forward a sheet along said support, an endless belt support- 130

ed so that a portion thereof is parallel with said support, means to move said belt continuously, a movable member on said belt and having a portion thereof extending into 5 the path of a sheet on said support to be operated by a sheet under the control of said forwarding means, said couple separating means being provided with a member to engage said movable member and to be moved 10 thereby, to throw said couple separating means into operation.

25. A printing couple, means to separate said couple, sheet taking means on said couple, means to forward a sheet toward and 15 into said sheet taking means, a gage, means to support and move said gage into, parallel with and out of the path of a sheet while it is being forwarded toward the taking point of said sheet taking means, and means 20 moving with said gage and controlled by the sheet being fed, to operate said couple separating means according to whether or not the sheet is positioned against said gage at a predetermined point in said gage's travel 25 toward said sheet taking point.

26. A printing couple, means to trip said couple, a trip controlling means to throw said tripping means into operation, a lever, means to oscillate said lever in timed relation to said couple, a pivoted member on 30 said lever, a gage, and sheet controlled means having a portion thereof adjacent said gage to move said pivoted member into engagement with said controlling means.

35 27. A printing couple, means to separate

said couple, a movable member to control the operation of said separating means, a sheet support for a sheet being fed to said couple, a front gage, an endless belt to support said gage, means to support and move said belt 40 so that said gage moves into, parallel with and out of the plane of said sheet support, a pivoted member on said belt adjacent said gage, and adapted to be moved by a sheet moving against said gage, a connecting 45 member, means to move said connecting member in timed relation to said couple, said pivoted member, said connecting member and said movable member being constructed and arranged so that said pivoted 50 member may engage said connecting member to move the latter into operative relation with said movable member.

28. A printing couple, means to forward a sheet toward said couple, a gage, means 55 to support and move said gage in the path of a sheet in the control of said forwarding means, a movable member adjacent said gage, and arranged to be moved by a sheet positioned against said gage and means arranged to hold said movable member in either one of two predetermined positions, according to whether or not a sheet is positioned against said gage at a predetermined 60 point of its travel.

JOSEPH WHITE.
